TOY TOP WITH DETACHABLE PARTS

Frederic A. Roberton, Oak Park, and James J. Gonsch, Chicago, Ill.

Application October 23, 1952, Serial No. 316,468

13 Claims. (Cl. 46—67)

This invention relates to a novel rotating toy and more particularly to a novel toy top having centrifugally detachable portions.

Various types of toy tops having centrifugally responsive operating characteristics have been proposed heretofore. For example, it has been suggested to provide a "flying" top wherein pivoted wing members swing outwardly during high speed rotation of the top to cause the device to rise in the air.

However, our invention is directed to a novel arrangement involving a plurality of detachable parts which can be assembled into a unitary top and retained in assembled relation during rotation of the top at high speeds. As the top slows down, certain of the parts automatically become detached and are thrown or scattered by centrifugal force to provide a unique and entertaining innovation in this class of toys.

Accordingly, a primary object of our invention is to provide a multiple part toy top having novel centrifugally responsive operating characteristics.

Another object of the invention is to provide a novel multiple-part toy top capable of providing amusement and entertainment not only during spinning of the top but by assembly and disassembly thereof.

A further object of the invention is to provide a novel toy top comprising a plurality of detachably connected parts adapted to be retained together in assembled relation during high speed rotation of the top but capable of being automatically detached and centrifugally scattered at a predetermined low speed of rotation.

Other objects and advantages of the invention will become apparent from the subsequent detailed description taken in conjunction with the accompanying drawing wherein:

Fig. 1 is a perspective view of one specific embodiment of our invention in assembled relation, the detached relation of the parts being partially illustrated in broken lines;

Fig. 2 is a vertical cross-sectional view through the device shown in Fig. 1;

Fig. 3 is a fragmentary top plan view with a part thereof in section as taken along the line 3—3 of Fig. 2;

Fig. 4 is a top plan view of a different embodiment of the invention; and

Fig. 5 is a fragmentary side elevational view showing the manner of operating the device illustrated in Fig. 4.

Broadly speaking, the novel toy top of our invention comprises a rotatable base and a plurality of detachable members or segments adapted to be fitted on the base in assembled relation. The detachable members are preferably sector-shaped so as to provide a unitary disk portion rotatable with the base when assembled thereon. The invention also contemplates the provision of releasable retaining means adapted to hold the detachable members in assembled relation during high speed rotation of the top but releasable at a predetermined low speed of rotation in order to permit the detachable members to be thrown or scattered centrifugally from the rotating base. As will hereinafter appear, the releasable retaining means

2

may take several different forms. Another broad feature of the invention resides in the provision of hub portions on the detachable segments which are adapted to have a spinning string wound therearound, the string thereby serving the additional purpose of holding the parts in assembled relation prior to actual spinning of the top.

Referring first to Figs. 1 to 3 of the drawing, this embodiment of the invention comprises a rotatable base 11, which may be of plastic or the like, having a tapered lower end 12 serving as a spinning or gyration point for the top and a flat upper surface 13. An upright spindle 14 having an upper cylindrical portion 16 and a lower portion 17 of polygonal cross-section, triangular in this instance, extends upwardly from the base 11 above the surface 13. The spindle 14 is preferably of metal and the triangular portion 17 is provided at its lower end with suitable corner teeth or serrations 18 in order to provide a rigid press fitted connection with the plastic base 11. A detachable handle member 19 having an axial bore 20 is also provided for rotatably receiving the upper end 16 of the spindle during initial spinning of the top.

A plurality of detachable members or segments 21, three being shown in this instance, are disposed on the upper flat surface 13 of the base 11. Preferably, the detachable members 21 are generally sector-shaped so that they may be fitted together in edgewise abutment around the spindle 14 in order to provide a disk portion extending radially outwardly from the base 11 and rotatable therewith. The inner end of each of the segments 21 carries an upright hub portion 22, each of the hub portions being so formed as to provide a unitary circular hub surrounding the spindle 14 when the segments 21 are assembled on the base 11. The outer periphery of each hub portion 22 has an inwardly curved contour so as to provide an annular groove or recess 23 for receiving a winding string 24. The outer corners of each hub portion are preferably cut away or beveled so as to provide a notch 26 between the adjacent corners for anchoring one end of the spinning string. It will be seen that in this embodiment of the invention the inner side of each hub portion 22 has a flat surface 27 adapted to be disposed in parallel relation closely adjacent one of the flat sides of the triangular spindle portion 17.

As will be apparent from the drawing, the outer blade portions of the segments 21 extend radially outwardly to a considerable extent beyond the rotating base 11 and because of the sector shape of the segments the area and weight of the overhanging portions are substantially greater than the area and weight of the inner portions in contact with the base 11. Consequently, the segments 21 are normally unstable and tend to tilt or rock downwardly and outwardly from the base 11 in the manner illustrated in broken lines in Fig. 2. However, when the parts of the top are assembled initially prior to spinning, it will be seen that the winding of the string 24 around the coacting hub portions 22 serves to bind or secure the tilttable segments 21 in non-tilted assembled relation on the base 11. Referring to Fig. 5 for a moment, it will be understood that the top is spun by grasping the detachable handle portion having the spindle journaled therein and pulling on the free end of the wound string in order to effect rotation of the device.

When spinning movement has thus been effected and the string is completely released and the handle portion removed, centrifugal force acting on the detachable segments 21 tends to throw the segments from the rotating base. However, we provide a releasable retaining means for holding the segments on the base during the initial period of high speed rotation of the device. To this end, each of the segments 21 is formed with an enlarged bore or opening 28 at the underside thereof and adjacent the inner end. A retaining pin 29 extends upwardly from the

flat surface 13 of the base 11 and is received in each of the openings 28. Thus, as the top rotates at high speed, the pins 29 prevent the segments 21 from being thrown centrifugally from the rotating base 11 and consequently the base 11 and the assembled segments 21 rotate in a unitary manner. At the same time, the centrifugal force acting on the segments 21 tends to hold the latter in substantially horizontal non-tilted relation so that the pins 29 are effectively positioned in the openings 28.

As the speed of rotation of the top decreases, a point is finally reached at some predetermined low speed of rotation at which the centrifugal force acting on the segments 21 is insufficient to overcome the overhanging weight of the segments with the result that at approximately the same time each of the segments tilts downwardly and outwardly in the manner shown in broken lines in Fig. 2. As the segments 21 rock or tilt about the peripheral edge of the rotating base 11, it will be seen that the pins 29 are automatically disengaged from the openings 28 at which point the segments being detached are then thrown centrifugally from the rotating base 11 providing a unique and entertaining effect.

The openings 28 being slightly larger than the diameter of the pins 29, it will be understood that the segments 21 are shiftable to a slight degree on the base 11 even when the pins 29 are in engagement in the openings 28. When the string 24 is wound around the hub portions 22, the segments 21 are drawn radially inwardly so that the pins 29 abut against the outer edges of the openings 28 leaving a slight clearance or space radially inwardly of each pin 29, as indicated at 30 in Fig. 2. However, upon spinning the top and releasing the string, the effect of centrifugal force causes the segments to shift outwardly until the pins 29 contact the inner peripheral edges of the openings 28 at which point they are retained until the centrifugal effect is insufficient to counteract the tipping moment of the overhanging segments.

Inasmuch as the segments 21 rock about the outer edge of the base 11 as a fulcrum, it will be seen that the vertical height of the pins 29 tends to prevent tilting release of the segments by rocking thereof while in their centrifugally urged positions in contact with the retaining pins 29. Consequently, in order to be released, the segments 21 must shift radially inwardly relative to the base 11 until the arcuate swinging movement of the inner ends of the segments allows the openings 28 to swing clear of the upright pins 29. Thus, the overhanging weight of the blade portions of the segments 21 must be great enough to produce the necessary inward camming of the segments which is in opposition to the effect of centrifugal force. Because of the necessity for this slight inward shifting of the segments before release thereof, it will be seen that the segments tend to be retained on the rotating base for a greater length of time and until a slower speed of rotation is reached than would otherwise be the case with a different retaining means. It will also be understood that the enlargement of the holes 28 relative to the pins 29 affords the needed clearance for accommodating the inward shifting of the segments prior to complete tilting and release thereof. Of course, enlargement of the holes 28 also facilitates and simplifies the initial assembly of the toy.

In the embodiment shown in Figs. 4 and 5, substantially the same principle is involved but in this case the retaining means for the detachable segments, indicated at 31, comprises coacting portions between the adjacent segments rather than between the base and each of the segments. Thus, one of the side edges of each of the sector-shaped segments 31 is provided with an irregular L-shaped opening or slot 32 and the abutting edge of the adjacent segment is provided with a complementary L-shaped projection 33 adapted to be received in the opening 32 and to provide an interlocking detachable connection therewith. Thus, the plurality of segments 31 are assembled in this case on the base of the top in much the same

manner as a simple jig-saw puzzle thereby imparting an additional amusement feature to the toy.

In this embodiment of the invention the rotating base, indicated at 34, has a smoothly tapered configuration and is of much smaller radial extent in order to provide a greater degree of overhang of the detachable segments 31 relative to the base 34. Another modification as compared with the first-described form of the invention resides in the shape of the inner surfaces of the hub portions. Thus, each hub portion, indicated at 36, has a generally V-shaped notch or groove 37 adapted to fit around one of the corner edges of the triangular spindle portion 17. In addition, the removable handle portion, designated at 38, in this form of the invention differs somewhat in shape from the handle 19 of the previous form but functions in the same manner.

It will be understood that in this modification of the invention the segments 31 are likewise tiltable relative to the base 34 and when such tilting movement takes place at a predetermined low speed of rotation, the interlocking fit of the projections 33 in the slots 32 is disrupted to permit the segments 31 to be detached from each other and thrown from the rotating base 34. For proper mutual disengagement of the segments 31 it is desirable that each segment tilt or rock about an axis substantially perpendicular to its radial center line. However, the projection 33 extending from one side of each segment and the slot 32 at the opposite side thereof result in a non-uniform or non-symmetrical weight distribution in each segment. The effect of such uneven weight distribution during tilting is overcome by means of the V-shaped notches 37 in the hub portions 36, these notches fitting rather closely around the spindle corners so that the spindle corners actually guide the segments during their tilting movement and insure tilting of each segment about an axis substantially perpendicular to its radial center line.

As an added feature of the device, each of the detachable segments may be decorated in different colors or patterns to provide any desired optical effect during rotation of the device. The rotating base is preferably molded from a relatively hard rigid plastic having suitable structural strength. The detachable segments, or at least the radially extending blade portions thereof, are preferably formed from a softer and relatively flexible material, e. g. polyethylene plastic, in order to avoid injury or damage when the segments are thrown from the rotating base. It will be evident that the distance of scatter of the detachable segments and the time at which the segments are released can be controlled to a certain degree by varying the structural relationship of the various parts of the device. For example, in the first-described form of the invention, variation in these operating characteristics may be obtained by changing the radial position and height of the retaining pins 29 and by varying the weight and extent of overhang of the blade portions of the detachable segments 21.

Although the invention has been described with particular reference to certain specific structural embodiments, it will be understood that various modifications and alternative constructions may be obtained without departing from the scope of the invention as defined in the appended claims.

We claim:

1. A toy top comprising a rotatable base, a plurality of detachable segments adapted to be assembled on said base, said segments having portions extending radially beyond said base and said segments being tiltable outwardly relative to said base, means coacting with said segments for initially holding the segments in non-tilted assembled relation on said base prior to spinning of the top, and retaining means responsive to centrifugal force acting upon said segments for holding said segments in non-tilted assembled relation on said base during high speed rotation of the top, said retaining means being releasable in response to outward tilting of said segments

at a predetermined low speed of rotation of the top whereby to permit said segments to be thrown centrifugally from the rotating base.

2. A toy top comprising a rotatable base, an upright spindle on said base, a plurality of detachable segments adapted to be assembled on said base around said spindle, said segments having coating hub portions adapted to fit around said spindle and to have a spinning string wound therearound, said segments also having portions extending radially beyond said base and being tiltable outwardly relative to said base, and releasable retaining means responsive to centrifugal force acting upon said segments for holding said segments in assembled relation on said base during high speed rotation of the top, said retaining means being releasable in response to outward tilting of said segments whereby to permit said segments to be thrown centrifugally from the base at a predetermined low speed of rotation.

3. The device of claim further characterized in that it also comprises a removable handle member having an opening to receive the end of said spindle for journaling the same during spinning of the top.

4. A toy top comprising a rotatable base, an upright spindle on said base adapted to be journalled in a handle member during spinning of the top, a plurality of detachable segments adapted to be assembled on said base around said spindle, said segments extending radially from said base in overhanging relation therewith such that said segments normally tend to rock outwardly relative to said base, upright hub portions carried at the inner ends of said segments and adapted to fit around said spindle and to have a spinning string wound therearound, the wound spinning string thereby initially holding said segments in assembled position on said base, and releasable retaining means coating with said segments for holding the latter in assembled relation on said base during high speed rotation of the top, said retaining means being releasable in response to outward rocking of said segments at a predetermined low speed of rotation of the top whereby to permit said segments to be thrown centrifugally from the rotating base.

5. A toy top comprising a rotatable base having a lower gyration point and a flat upper portion, a spindle extending upwardly from said base and adapted to be journalled in a handle during spinning of the top, a plurality of detachable sector-shaped members adapted to be assembled flatwise on the flat upper portion of said base and extending radially therefrom to provide a disk portion rotatable with said base, said members being tiltable outwardly relative to said base, a plurality of upright hub portions carried at the inner radial ends of said members and adapted to fit around said spindle and to receive a winding string for spinning the top, and releasable retaining means for holding said members in flatwise assembled relation on said base during high speed rotation of the top, said retaining means being releasable in response to outward tilting of said members whereby to permit said members to be released and thrown centrifugally from the base at a predetermined low speed of rotation.

6. A toy top comprising a rotatable base, a plurality of detachable segments adapted to be disposed in assembled relation on said base, said segments having portions extending radially beyond said base and being tiltable outwardly relative to said base, each of said segments having an opening therein, and retaining means responsive to centrifugal force acting upon said segments and coating with the openings in said segments for retaining the latter in non-tilted assembled relation on said base during high speed rotation of the top, said retaining means being releasable in response to outward tilting of said segments whereby to permit said segments to be released and thrown centrifugally from said base at a predetermined low speed of rotation.

7. A toy top comprising a rotatable base, a plurality of detachable segments provided with openings at the under-

sides thereof and adapted to be assembled on said base, said segments having portions extending radially beyond said base and being tiltable outwardly relative to said base, and a plurality of pins projecting from said base and receivable within said openings and cooperable with the latter in response to centrifugal force acting on the segments for retaining said segments in non-tilted assembled relation on said base during high speed rotation of the top, said segments being tiltable outwardly relative to said base at a predetermined low speed of rotation whereby to disengage said pins from said openings and to permit said segments to be thrown centrifugally from the rotating base.

8. A toy top comprising a rotatable base, a plurality of detachable sector-shaped members adapted to be assembled on said base and extending radially outwardly therefrom to a sufficient extent so that said members normally tend to tilt outwardly from said base, upright hub portions carried at the inner ends of said members and adapted to have a spinning string wound therearound whereby the string initially holds said members in non-tilted assembled relation, said members each having an opening at its underside over said base, and a plurality of retaining pins on said base and adapted to extend into the openings in said members whereby the latter are retained in non-tilted assembled relation on the base during high speed rotation of the top, said members being adapted to tilt outwardly from the base at a predetermined low speed of rotation whereby to disengage said pins from said openings and to permit said members to be thrown centrifugally from the rotating base.

9. The device of claim 8 further characterized in that said openings are slightly larger than said pins whereby to permit the tilting forces acting on said members to cause slight inward shifting of the members on said base for permitting said openings to swing clear of said pins.

10. A toy top comprising a rotatable base, a plurality of detachable segments adapted to be assembled on said base, said segments having portions extending radially beyond said base and being tiltable outwardly relative to said base, and releasable retaining means coating between adjacent segments for holding the latter in non-tilted assembled relation on said base during high speed rotation of the top, said retaining means being releasable in response to outward tilting of said segments at a predetermined low speed of rotation for disengaging said retaining means whereby to permit said segments to be thrown centrifugally from the rotating base.

11. A toy top comprising a rotatable base, a plurality of detachable segments adapted to be fitted together in assembled relation on said base, said segments having portions extending radially beyond said base and being tiltable outwardly relative to said base, and retaining means comprising a plurality of interlocking openings and projections provided in the abutting edges of said segments whereby to retain said segments in non-tilted assembled relation on said base during high speed rotation of the top, said retaining means being releasable in response to outward tilting of said segments at a predetermined low speed of rotation whereby to disengage said openings and projections and to permit said segments to be thrown centrifugally from the rotating base.

12. A toy top comprising a rotatable base, a plurality of detachable sector-shaped members adapted to be assembled on said base and extending radially outwardly therefrom to a sufficient extent so that said members normally tend to tilt outwardly from said base, upright hub portions carried at the inner ends of said members and adapted to have a spinning string wound therearound whereby the string initially holds said members in non-tilted assembled relation, and retaining means comprising a plurality of complementary interlocking edgewise openings and projections provided in the abutting sides of said members whereby said members are retained in unitary non-tilted assembled relation on said base during high speed rotation

of the top, said members being adapted to tilt outwardly from the base at a predetermined low speed of rotation whereby to disengage said projections from said openings and to permit said members to be thrown centrifugally from the rotating base.

13. The device of claim 12 further characterized in that said base has an upright spindle with corner edges and said hub portions on said members are provided with grooved portions coacting with the corner edges of said spindle for insuring tilting movement of each of said members about an axis substantially perpendicular to its radial center line.
